COLLAPSIBLE TOOL CABINET UNIT

William E. Greene, New York, N. Y.

Application February 27, 1936, Serial No. 65,941

4 Claims. (Cl. 312—1)

This invention relates to new and useful improvements in a collapsible tool cabinet unit.

The invention has for an object the construction of a unit as mentioned which is characterized by a flat vertical member supporting a tool cabinet, a drawer cabinet, a motor driven buffer and emery wheel, and a work table.

More particularly, it is contemplated to so arrange the various parts that the flat vertical member may comprise the door of a closet or other similar element. When thus constructed, the tool cabinet is inconspicuous and at the same time convenient to be used when desired.

A further object of this invention is to arrange the table board adjustable so that it may be extended outwards when used and moved flat against the vertical member when not used.

Still further the invention proposes to arrange a door for closing the tool cabinet and to provide a mechanism for automatically moving the table board up to the horizontal working position when the door of the cabinet is opened.

Another object of this invention is to arrange a movable light upon the flat vertical member so that proper illumination may be had when the device is being used.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a perspective view of a closet door used in conjunction with the collapsible tool cabinet unit according to this invention.

Fig. 2 is a perspective view similar to Fig. 1 but showing the tool cabinet door open and the table board in the horizontal position.

Fig. 3 is a vertical sectional view taken on the line 3—3 of Fig. 2.

Fig. 4 is a fragmentary enlarged detailed view of a portion of Fig. 3.

Fig. 5 is a fragmentary horizontal sectional view taken on the line 5—5 of Fig. 3.

Fig. 6 is a fragmentary horizontal sectional view taken on the line 6—6 of Fig. 3.

Fig. 7 is a fragmentary enlarged detailed view of a portion of Fig. 3.

Fig. 8 is a sectional view taken on the line 8—8 of Fig. 7.

The collapsible tool cabinet unit, according to this invention, includes a flat vertical member 10, which preferably, is a door of a closet,

with various cabinet units and tools mounted on the upper portion of the vertical flat member 10. This tool cabinet is provided with a door 12 which is hingedly mounted at one side so that it may be opened, as clearly shown in Figs. 1 and 2. Within the cabinet there are a plurality of clamps 13 which support a plurality of tools 14.

Beneath the tool cabinet 11 a drawer cabinet 15 is mounted and attached to the flat vertical member 10. This drawer cabinet includes a plurality of horizontal partitions 16 supporting a plurality of drawers 17. These drawers may be used to store and hold nails, screws and other small objects.

A motor driven buffer and emery wheel 18 is mounted upon the vertical member 10 beneath the drawer cabinet 15. A table board 19 is hingedly mounted at one side upon the vertical member 10 and is adapted to be moved up to a horizontal position, as shown in Fig. 2, or down to a vertical position as shown in Fig. 1. A means is provided for holding this table board in the vertical position.

It comprises a pair of collapsible arms 20 at each of the sides of the table board connected between the extremities of the board and the vertical member 10. Each of

these arms comprises an upper arm section 20^a and a lower arm section 20^b pivotally connected in such a manner that in an aligned position of the arms they may be moved to a position so that they no longer can pivot. This is accom-

plished by a square projection 21 from the lower end of the arm 20^a engaging through an opening 22 in the upper end of the section 20^b.

The opening 22 has a circular portion 22^a at the top connecting with a lower square shaped portion 22^b. The square projection 21 is pro-

vided with a large head 23 which is capable of extending over the opening 22 so that the parts are slidably and pivotally connected. The upper ends of the arm sections 20^a are pivotally con-

nected with the outer end of the table board 19. The lower ends of the arm sections 20^b are pivotally connected on brackets 23 mounted on the vertical member 10.

A means is also provided for automatically raising the table board 19 to the operative horizontal position when the door 12 of the tool cabinet is opened. This means comprises an arm 25 projecting from the hinge edge of the door 12 and adapted to swing in an arcuate path as the door 12 is opened and closed.

A link 26 is hingedly connected with the outer end of the arm 25 and loosely connects with the upper arm 27^a of a bell crank 27 which has a lower arm 27^b. This lower arm has a slot into which a pin 28 extends.

The pin 28 is mounted on a rod 29 which extends downwards and is slidably supported by engaging through bearings in the back of the drawer cabinet 16 and in the base of the motor driven cabinet 18 and in the base of the motor driven buffer 18. At the lower end rod 29 has rack teeth 29^a which mesh with a small pinion 30 fixed on a shaft 31 which is rotatable in a support bracket 32 mounted on the vertical member 10. This shaft 31 is pinned to a lug 36 mounted 10 on the rear edge of the table board 19.

When the door 12 is opened the bell crank 27 will be pivoted so that the rod 29 is moved downwards which will turn the pinion 30 to move the table board 19 upwards. When the table board 15 reaches the horizontal position it automatically is locked into this position by reason of the square projection 21 engaging into the square opening 22^b, immediately upon releasing of the door 12. In order to reclose the door 12, or lower 20 the table board 19, it is necessary that the table board be slightly raised so that the projection 21 engages in the opening 22^a and then the arm sections 20^a and 20^b may be pivoted to prevent the projection 21 from re-engaging in the opening 22^b. The arms 21^a and 21^b may now move 25 downwards and assume the dot and dash position indicated in Fig. 3.

An electric plug 38 is mounted upon the vertical member 10 and is wired (not shown on the drawing) to a lamp 39 on a pivotally mounted arm 40. The plug 38 may be connected with a conventional house circuit to illuminate the lamp. Since the arm 40 may be pivoted, the lamp may be placed in advantageous positions when the 35 device is used.

While I have illustrated and described the preferred embodiment of my invention, it is to be understood that I do not limit myself to the precise construction herein disclosed and the 40 right is reserved to all changes and modifications coming within the scope of the invention as defined in the appended claims.

Having thus described my invention, what I claim as new, and desire to secure by United 45 States Letters Patent is:—

1. A collapsible tool cabinet unit, comprising a flat vertical member, a tool cabinet mounted thereon and having a hinged door, a table board hingedly mounted on said member and adapted 50 to normally depend, means for raising said table board to the horizontal position operated by the opening of said door, and means for latching said table board in the horizontal position, said latter means comprising a pair of hingedly connected

arms connected at their outer ends with the table board and with said flat vertical member and at their inner ends being provided respectively with a square rod on one of the parts engaging in a keyhole slot in the other of the parts. 5

2. A collapsible tool cabinet unit, comprising a flat vertical member, a tool cabinet mounted thereon and having a hinged door, a table board hingedly mounted on said member and adapted to normally depend, means for raising said table 10 board to the horizontal position operated by the opening of said door, comprising a support bracket mounted on said vertical member, a pinion rotatably supported on said bracket, a rod having rack teeth upon its lower end engaging 15 with said pinion, and means for connecting said rod and hinged door to lower said rod when said door is opened and so raise said table board when said cabinet is opened.

3. A collapsible tool cabinet unit, comprising 20 a flat vertical member, a tool cabinet mounted thereon and having a hinged door, a table board hingedly mounted on said member and adapted to normally depend, means for raising said table board to the horizontal position operated by the 25 opening of said door, comprising a pinion coaxially mounted with relation to said hingedly mounted table board, a rod having rack teeth upon its lower end engaging with said pinion, and means for connecting said rod and hinged door to lower said rod when said door is opened 30 and so raise said table board when said cabinet is opened.

4. A collapsible tool cabinet unit, comprising 35 a flat vertical member, a tool cabinet mounted thereon and having a hinged door, a table board hingedly mounted on said member and adapted to normally depend, and means for raising said table board to the horizontal position operated 40 by the opening of said door, comprising a pinion coaxially mounted with relation to said hingedly mounted table board, an arm extending from the edge of said door, a link connected at one end with the outer end of said arm, a bell crank pivotally mounted on the side wall of said cabinet, one arm of said bell crank being connected to the other end of said link, a rod having one of its ends connected with the other arm of said bell crank, and the other end of the rod having rack teeth engaging said pinion to move said 45 table to the operative position when said door is opened. 50
